UNITED STATES PATENT OFFICE.

WILLIAM D. SHERMAN, OF SANDY HILL, NEW YORK, ASSIGNOR OF ONE-HALF TO CORNELIUS BLOOMINGDALE, OF SAME PLACE.

DESIGN FOR A MILK-COOLER.

SPECIFICATION forming part of Design No. 29,509, dated October 18, 1898.

Application filed September 15, 1898. Serial No. 691,045. Term of patent 7 years.

To all whom it may concern:

Be it known that I, WILLIAM D. SHERMAN, a citizen of the United States, residing at Sandy Hill, in the county of Washington and State of New York, have invented and produced a new and original Design for Milk-Coolers, of which the following is a specification, reference being had to the accompanying drawings, forming part thereof.

My invention relates to a new and original design for milk-coolers.

In the accompanying drawings, Figure 1 is a view in perspective. Fig. 2 is a vertical section, and Fig. 3 is a plan view.

As shown in the accompanying drawings, A represents the cylindrical body, 1 the con-

ical upper portion, and 2 the handle. The cylindrical lower portion is open at the bottom, and at the upper end of the conical portion 1 a small curved or bent tube 4 is arranged, the latter opening in the surface of the conical portion and also in the interior of the design.

Having fully described my invention, what I claim as new, and desire to secure by Letters Patent, is—

The design for a milk-cooler, substantially as shown and described.

WILLIAM D. SHERMAN.

In presence of—

ALVAN D. ARNOLD,
WILLIAM E. YOUNG.
